UNITED STATES PATENT OFFICE

2,633,212

GROUND ANCHOR

Alwin G. Steinmayer, Milwaukee, Wis., assignor
to McGraw Electric Company, a corporation
of Delaware

Application August 2, 1949, Serial No. 108,155

3 Claims. (Cl. 189—92)

1

This invention relates to ground anchors.

Ground anchors are employed to secure guy wires. The ground anchors are usually inserted in a hole which is of smaller diameter than the expanded width or diameter of the ground anchor and when so inserted, the blades or flukes are forced outwardly so that they dig into and underhang the undisturbed ground. Thereafter the hole is refilled above the blades.

Objects of this invention are to provide a ground anchor of the expanding type which may be made of a very small number of parts and, except for the anchor rod, may be formed of stampings from heavy sheet metal, thus materially reducing the cost of manufacture.

Further objects are to provide an expanding ground anchor which may be shipped to the customer either in the knock-down or in the assembled condition to thus conserve the space required for packing, and which is arranged to use identical flukes or blades so that one die can serve to form both blades, and in which the blades are interlocked and are held against detachment from each other by means of the anchor rod.

An embodiment of the invention is shown in the accompanying drawings, in which:

Figure 1 is a side elevation of the anchor.

Figure 2 is a plan view of one of the blades or flukes before the interlocking tongues have been bent.

Figure 3 is a fragmentary view corresponding to a portion of Figure 2 showing in imaginary lines the second blade and showing the blades in their interlocking relation.

Figure 4 is a view corresponding to Figure 1 but taken at right angles to that of Figure 1 and showing the ground anchor broken off.

Figure 5 is an enlarged sectional view on the line 5—5 of Figure 4.

Figure 6 is a view showing the anchor in expanded position.

Referring to the drawings, it will be seen that the ground anchor comprises a pair of blades or flukes indicated by the reference character 1, which are of identical construction and which are stamped from heavy sheet metal. These blades are provided with tongues 2 which are spaced from the body portion by means of slots 3 and are provided with a centrally located approximately semi-circular notch or opening 4. If desired, the blades may be provided with tongues 5 which act temporarily as locking members as will be explained hereinafter.

The base of the anchor or, in other words, the member which is effective in expanding or spreading the blades is indicated by the reference

2

character 6 and is a stamping of heavy sheet metal and is circular in contour. It is generally of the shape of a truncated cone and has slanting substantially conical sides or faces 7, and for strengthening purposes has a depressed central or cup-shaped portion 8 as shown most clearly in Figure 1. It is also provided with diametrically opposed holes 9 which temporarily receive the tongues 5 of the blades or flukes 1. The base 6 is centrally apertured and an anchor rod 10 passes therethrough. This anchor rod has its lower portion threaded and receives the nut 11 which bears against the depressed portion 8 of the base. The upper end of an anchor rod is formed as an integral eyelet and is adapted to receive the guy wire.

Figure 5 shows the manner in which the small locking tongues temporarily interlock with the body portion. This is merely to hold the blades in place while they are being inserted into the hole and as soon as the blades are spread, the temporarily effective locking tongues 5 slide freely from the openings 9.

It is to be understood that the tongues 2 are bent over after the blades have been initially stamped from the sheet metal and are interlocked and occupy the position shown in Figure 1 when the anchor is not expanded, and they occupy the position shown in Figure 6 when the anchor is expanded. It is also to be noted that the blades or flukes 1 are slightly dished so that they will freely dig into the ground and also will, because of this shape, have a little firmer or more effective anchoring effect.

In using the device, the hole of the proper diameter, slightly greater than that of the base 6, is dug in the ground and the anchor is inserted in its closed condition shown in Figure 1. Thereafter a pounding member, not shown, is used to pound downwardly on the heels of the curved portions 13 of the blades and to thus cause the blades to travel outwardly to the position shown in Figure 6 by coacting with the expanding member or base 6.

If desired, the anchor may be shipped to the customer in knock-down condition and he may thereafter assemble it or it can be shipped to the customer in its fully assembled condition as shown in Figure 1.

It will be seen that a very simple and cheaply produced ground anchor has been provided most of whose parts are formed from stampings.

It will also be seen that a minimum number of parts are employed and that a very secure anchoring effect is obtained.

Although this invention has been described in

considerable detail, it is to be understood that such description is intended as illustrative rather than limiting, as the invention may be variously embodied and is to be interpreted as claimed.

I claim:

1. A ground anchor for guy wires comprising a pair of opposed flukes having bayonet slots providing detachably interlocking tongues and each fluke provided with an approximately centrally located cut-out portion, an anchor rod passing through the cut-out portion in each of said flukes and preventing detachment of said interlocking tongues, and a spreading member for spreading said tongues carried by the lower end of said anchor rod, said anchor rod having a guy wire receiving means at its upper end, the slots in one fluke having a loose fit with the tongues of the other fluke to provide free hinging of the flukes.

2. A ground anchor for guy wires comprising a pair of identical flukes positioned back to back and having bayonet slots providing laterally interlocking tongues which are laterally detachable from each other and each fluke having an approximately centrally located cut-out portion, an anchor rod passing through the cut-out portions of said flukes and preventing lateral detachment of said tongues, said anchor rod having guy wire receiving means at its upper end, and a spreading member carried by the lower end of said anchor rod, the slots in one fluke having a loose fit with the tongues of the other fluke to provide free hinging of the flukes.

3. A ground anchor for guy wires comprising a pair of identical flukes positioned back to back and having bayonet slots providing laterally interlocking tongues which are laterally detachable from each other and each fluke having an approximately centrally located cut-out portion, an anchor rod passing through the cut-out portions of said flukes and preventing lateral detachment of said tongues, said anchor rod having guy wire receiving means at its upper end, and a spreading member carried by the lower end of said anchor rod, said interlocking tongues having bent portions providing heels which constitute surfaces that may be bounded on during spreading operation of said flukes, the slots in one fluke having a loose fit with the tongues of the other fluke to provide free hinging of the flukes.

ALWIN G. STEINMAYER.
